(57) **CLAIM**

The ornamental design for a electric grill, as shown and described.

DESCRIPTION

FIG. 1 is a first perspective view of the electric grill;
 FIG. 2 is a exploded view of the electric grill;
 FIG. 3 is a right side view of the electric grill;
 FIG. 4 is a left side view of the electric grill;
 FIG. 5 is a front view of the electric grill;
 FIG. 6 is a back view of the electric grill;
 FIG. 7 is a top view of the electric grill; and,
 FIG. 8 is a bottom view of the electric grill.
 The broken lines shown in the drawings are for illustrative purposes only and form no part of the claimed design.
